UNITED STATES PATENT OFFICE.

FRANK VALIN, OF FAIRFIELD, MAINE.

WINDOW-SASH.

SPECIFICATION forming part of Letters Patent No. 499,405, dated June 13, 1893.

Application filed January 10, 1893. Serial No. 457,965. (No model.)

To all whom it may concern:

Be it known that I, FRANK VALIN, a citizen of the United States, residing at Fairfield, in the county of Somerset and State of Maine, have invented a certain new and useful Improvement in Window-Sashes; and I do hereby declare the following to be a full, clear, and exact description of the invention, such as will enable others skilled in the art to which it appertains to make and use the same.

My invention relates to a window capable of being partially opened for the purposes of ventilation without raising the sash, and it is particularly adapted to outside or double windows which are usually fastened in cold weather to the outside of the window casing in such a way that they cannot be opened. When these windows are designed to admit air, they are made with one of the lights of glass hinged so that it can be swung open when air is to be admitted. It is found in practice exceedingly difficult to make these swinging panes tight so that the snow will not sift through or the rain enter in a storm. In my improved window I make the opening through the lower rail of the sash and it is so constructed that neither snow nor rain can be forced through. The opening is made by means of a tapering plug fitting a tapering recess formed in the under side of the rail and on the inner or larger end of the plug is a flange or offset. The inclination which is thus given to all the surfaces by which water or snow can enter effectually prevents their passage through the window.

I illustrate my invention by means of the accompanying drawings in which—

Figure 1. is a front view of the lower portion of a window fitted with my improvement.

Fig. 2. is a top view of the plug, and Fig. 3. is a section on the line xx of Fig. 1.

A is the sash of the window and A' is the lower rail. In the lower edge of the rail A' I form a recess which exactly fits the tapering plug a. This plug is preferably cut on an arc of a circle and on its inner or large end there is a flange or offset a'. A handle b is provided for removing the plug and a button or other similar fastening device is provided to retain it in place when the window is in position. It will be observed that the surfaces of all the openings through which the rain or snow can come are inclined so that they are thereby readily excluded while the offset a' makes an additional protection in this respect.

The plug can be readily taken out and put back in place and it is easily and cheaply made.

I claim—

1. The herein described ventilated window having a tapering recess formed in the under side of the lower sash rail and a tapering plug fitting said recess, substantially as described.

2. The herein described ventilated window having a recess formed in the under side of the lower sash rail and a tapering plug fitting said recess the inner or larger end of said plug having a flange or offset, substantially as described.

In testimony whereof I affix my signature in presence of two witnesses.

FRANK VALIN.
